JOINTER BED STRUCTURE

William B. Boice, Toledo, Ohio, assignor to Boice-Crane Company, Toledo, Ohio, a corporation of Ohio

Application February 9, 1951, Serial No. 210,251

9 Claims. (Cl. 144—129)

1

This invention relates to woodworking machines and particularly to jointers, and an object is to produce a new and improved frame structure for a jointer or the like to enable the employment of a longer table or working surface with the aim of increasing sturdiness and rigidity and obviating warping or misalignment of the table portions.

Another object is to produce jointer table supporting bed structures in which one is adjustable vertically relative to the other, the structures being formed from sheet metal and being provided with novel features of construction and arrangement hereinafter more fully described.

It is desired to produce a jointer having an exceedingly long table surface as compared to those presently in use. This requires an over-all table length of the order of eighty inches, and due to the greater length and the overhang relative to the supporting standard, the weight must be kept as low as possible and factors causing misalignment of one section of the table relative to the other, must be coped with, and in addition, the cost of the structure must be kept low in view of competitive conditions. An object is, therefore, to produce jointers having table supporting bed structures which satisfy these requirements.

For purposes of illustration but not of limitation, an embodiment of the invention is shown on the accompanying drawings, in which

Figure 1 is a side elevation of a jointer, a portion of the supporting standard being broken away;

Figure 2 is a top plan view of the jointer shown in Figure 1;

Figure 3 is a side elevation of the stationary table supporting bed;

Figure 4 is an end elevation of the bed shown in Figure 3 viewed from the left-hand end of Figure 3;

Figure 5 is a vertical sectional elevation on the line 5—5 of Figure 3;

Figure 6 is an end view of the bed shown on Figure 3 viewed along the line 6—6 of Figure 3;

Figure 7 is a top plan view of the bed shown in Figure 3;

Figure 8 is a perspective view of one of the gib-carrying subassemblies disposed between the side plates of the bed in the region of the downwardly inclined edge portion;

Figure 9 is a top plan view of the adjustable table supporting bed;

Figure 10 is a side elevation of the adjustable bed shown on Figure 9;

Figure 10A is an enlarged section on the line 10A—10A of Figure 9;

2

Figure 11 is an end elevation of the bed shown on Figure 9 taken substantially on the line 11—11 of Figure 9;

Figure 12 is a perspective view of one of the subassemblies fixed to the bed and disposed adjacent the lower end of the downwardly inclined edge portions; and

Figure 13 is a perspective view of the other of the subassemblies carried by the adjustable bed.

10 The illustrated embodiment of the invention comprises a jointer, which is mounted upon an elevated standard or support S and comprises a stationary table supporting bed structure A, on which an adjustable table supporting bed B is mounted for vertically inclined adjusting movements. Suitably carried by the stationary bed A is a rotary cutter C driven by an electric motor M. Mounted for bodily shifting movements transversely of the table surface is a fence F, which has a handle H and is provided at one end with a depending guide member F', which is secured in its adjusted position by a locking device L. Since the detail construction of the locking device and the jointer forms no part of the present invention, further description and illustration thereof is not considered necessary.

15 Mounted on the table is a suitable guard G which protects the operator from the rotary cutter C and bears laterally against a face of a work piece W, the other side of which abuts against the fence F as will be readily understood.

The stationary table supporting bed A comprises a pair of laterally spaced, upright, parallel, longitudinal sheet metal side plates 10 and 11, the lower edge portions of which are bent inwardly at substantially right angles to provide flanges 12, which extend from one end to the other. As shown in Figure 3, the lower left-hand end of the side plates 10 are inclined, as indicated at 13, whereas the remainder of the lower

20 edge portions, as indicated at 14, are flat to be supported by the supporting standard S. Approximately midway of the bed is a cross piece 15, the central portion 16 of which is arched upwardly in a position between the side plates. The

25 cross piece 15 is welded to the side walls and portions thereof extend beyond the opposite sides of the side walls, these portions being apertured to receive stud bolts or the like for securing the bed to the supporting standard. As shown at the extreme right-hand end of Figure 3, a similar cross piece 17 connects the side plates 10 and 11 and is welded in place, the cross piece 17 having a central aperture to receive a stud bolt or the like for securing the end portion of the bed to the support S.

30 35 40 45 50 55

A major portion of the upper edge of the side plates 10 and 11 is flat as indicated in Figure 3 and resting thereon is a longitudinal sheet metal plate 18, which provides a table top for the bed A. The right-hand end of the table thereby extends slightly beyond a cut-out portion 19 and to the outer side of each of the plates 10 and 11 is welded an arcuate bearing pad 20 to which bearing elements 21 (Figure 1) are bolted. At the right-hand end of the bearing pads 20 (Figure 3), the upper edge portions of the side plates incline downwardly as indicated at 22. It is along the edge portions 22 that the adjustable bed rides as will hereinafter appear.

Beneath the table 18 and for reenforcing and supporting the side plates 10 and 11 in upright position are transversely arranged sheet metal spacer plates 23, 24 and 25, which are welded in position. Near the left-hand end of the assembly is a flanged plate 26, which is welded to the side plate flanges 12 and the side plates for re-enforcing purposes. It will be apparent that the left-hand end (Figure 3) of the bed A is open and insertable therein may be a drawer (not shown), which is suspended from guide plates 27 depending from the under side of the table 18.

In the fabrication of the bed A, two subassemblies are welded to the right-hand end portion (Figure 3) to provide the gibs, on which the adjustable bed B is shifted as well as to space and reenforce that portion of the bed. These two subassemblies are similar to each other and differ only in the length of the transverse plates. As shown on Figure 8, each subassembly comprises a pair of spaced transversely arranged plates 28 and 29, each of which has a pair of upwardly projecting integral extensions 30 formed by cutting out an intermediate portion of the plate indicated at 31. To the upper ends of corresponding extensions 30 of the plates 28 and 29 are welded gibs 32. The plate 29 extends upwardly beyond the plate 28 as shown in Figure 3, thereby to effect proper spacing and reenforcing. It will be understood that the subassembly is first made up and then introduced between the side plates, the gibs inclining downwardly slightly below the inclined edge portion 22 and parallel thereto.

It will be observed that one subassembly is arranged adjacent the upper end of the inclined edge portions 22 and the other adjacent the lower end of these inclined edge portions. As shown particularly in Figure 6, the inner edge portions of the gibs 32 are inclined rearwardly, the inner edge being approximately flush with the outer edge of the respective extension 30. Intermediate the two subassemblies above described is a substantially inverted U-shaped flanged plate 33, which is spaced farther below the inclined edge portions 22. This plate is welded to the inner faces of the longitudinal side plates 10 and 11 and is formed with a central hole 34 for a purpose hereinafter to be described.

The adjustable table supporting bed B is similarly constructed of sheet metal and has a table top 35 to the under side of which are welded a pair of longitudinally extending, laterally spaced, parallel sheet metal plates 36 and 37. The right-hand portion (Figures 9 and 10) of the side plates inclines downwardly, as indicated at 38, and this portion of each of the side plates has inwardly extending longitudinal flanges 39. A transversely arranged sheet metal spacer and reenforcing plate 40 is arranged between the longitudinal plates 36 and 37 and is welded in place.

Closing the outer end of the bed B is a steel

casting having a vertically disposed, longitudinally slotted plate 42, which extends laterally to one side of the table and carries a table extension 41 on its upper portion. The longitudinal plate 37 abuts against the rear face of the plate 42 to which it is welded and the longitudinal plate 36 overlaps the other end of the plate 42 and is likewise welded to it. A space is left between the table extension 41 and the table 35 and this space is filled by weld 41a, which is subsequently ground and polished to present a flush table top. In order rigidly to secure the table 35 to the plate 42, the latter has a longitudinal groove 42a at its upper portion (Figure 10A) to receive weld 42b. Upper and lower guides 44 and 43 respectively are formed in the outer face of the plate 42 for suitably receiving and guiding the end plate F' of the jointer fence F.

It will be apparent that the table 35 extends laterally beyond the longitudinal upright plate 36 and welded to the under side of this extending portion is a plate 45, the lower edge of which is flanged inwardly as indicated at 46. The table 35 has a longitudinally extending portion 47 to overlap a portion of the table 18 of the fixed or stationary bed A.

The inner portions of each of the plates 36 and 37 have their edges upwardly and inwardly inclined, as indicated at 48, with an intermediate recessed portion 49, and interposed between these upright plates in the region of these upwardly inclined edge portions is a pair of subassemblies T and T', the subassembly T being adjacent the lower ends of these inclined edge portions, and the subassembly T' being adjacent the upper ends thereof. Each of these subassemblies incorporates guide strips for slidably engaging the gibs 32 in the stationary bed A, above described.

The subassembly T comprises a pair of rectilinear sheet metal plates 50, which are in laterally spaced parallel relationship. As shown, the plates 50 are relatively long and are welded at their side edge portions to the inner sides of the longitudinal upright plates 36 and 37. Each of the plates has a hole 51 in alignment with the hole in the other plate and integral with the lower edge of each plate 50 is an extension 52 which has a narrow neck 53, opposite side edges of which flare divergently outward. As shown in Figure 10, the extensions 52 of the plates 50 project outwardly beyond the inclined edge portions of the longitudinal plates.

Interposed between the two plates 50 and welded thereto is a pair of spacer plates 54, each of which engages the lower edge portion of each plate and also the subjacent outwardly flared portion of the extension 52, these spacer plates being welded at their ends to the plates 50 and extensions 52 in order rigidly to secure these parts together.

Connecting each pair of outwardly flared edge portions of the extensions 52 is a sheet metal strip 55, which is welded in place. The strips 55 slidably engage surfaces of the gibs 32, on the lower subassembly of the stationary bed A, and are somewhat longer than the gibs to allow for desired adjusting movement thereon.

The subassembly T' comprises a relatively short sheet metal plate 56, which is disposed between and welded to the longitudinal plates 36 and 37. This plate similarly has an extension 57 provided with a reduced neck 58, the extension having outwardly flared or divergent edge portions, as shown on Figure 13. Spaced laterally

75 from the plate 56 is a narrow plate 59 which is

similarly welded at its ends to the inner sides of the longitudinal plates 36 and 37. The plate 59 is inclined outwardly and connecting the inner side of the plate 59 to the plate 56 and extension 57 is a curved spacer plate 60, which is shaped to conform to the outwardly flared edge portions of the extension. Welded to the outer edge portions of the spacer plate 60 and the extension 51 on each side is a relatively narrow strip 61 which, as shown in Figure 10, is in alignment with the adjacent strip 55 of the subassembly T and accordingly projects outwardly from the inclined edge portion 48. It will be understood that the guide strips 61 of the subassembly T' are longer than the gibs 32 of the upper subassembly on the stationary bed A (Figure 3) and slidably engage same for guiding the vertically inclined adjusting movement of the adjustable bed B relative to the stationary bed A.

The mechanism for effecting adjustment of the bed B relative to the bed A appears on Figure 1 and as shown, a member 62 is mounted on the bracket 33 and is suitably held in position. The member 62 extends upwardly as shown and has a transverse screw-threaded hole adjacent the upper end to receive a screw-threaded rod 63. The rod 63 extends through the aligned holes 51 in the subassembly T so as to rotate therein. The screw-threaded rod is so mounted in the plates 50 of the subassembly T that it can rotate relatively thereto but cannot shift transversely. At the opposite end of the rod 63 is a bevel gear 64, which is engaged by a bevel gear 65 on one end of a shaft which has a hand wheel 66 at the outer end. By turning the hand wheel 66, it will be manifest that the bed B is caused to move inclinedly upwardly or downwardly relative to the stationary bed A. After the desired adjustment has been made through the operation of the hand wheel 66, L-shaped screws 67, which extend from the outside through holes in the longitudinal plate 10 of the stationary bed A and into screw-threaded holes 68 (Figure 8) in the adjacent gibs of the upper and lower subassemblies, are tightened for frictionally holding the parts stationary, a conventional floating gib (not shown) imposing a binding action against the strips 55 and 61 as will be readily understood by those skilled in this art.

The above described jointer frame structure is particularly advantageous in the case of exceedingly long tables where the overhang is substantial. Difficulty is experienced in these jointers when the parts are constructed for example of metal castings because not only are the castings so heavy that support is a problem, but also the true alignment of the table surface has in such cases not been achieved satisfactorily. By the improved sheet metal welded fabrication above described, not only can true and accurate table alignment be secured, but the weight as well as the cost of the structure is materially reduced. In addition, the strength, ruggedness and durability of the frame parts are greatly increased so that the useful life of the machine is noticeably prolonged.

It is to be understood that numerous changes in details of construction, arrangement and operation may be effected without departing from the spirit of the invention especially as defined in the appended claims.

What I claim is:

1. In a jointer having a stationary table supporting bed and an adjustable table supporting bed on the stationary bed, the stationary bed

comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one side of said inclined edge portions, a table top welded to the upper edge portions of said upright plates, a subassembly between said upright plates in the region of said inclined edge portions and welded thereto, said subassembly including a pair of upright transversely arranged plates with the advanced plate elevated above the other plate, extensions projecting upwardly at the side edge portions of said last plates, and a gib welded to the corresponding extensions of said plates, the gibs being inclined corresponding to that of said inclined edge portions and being arranged adjacent thereto, and means on said adjustable bed 20 slidably engaging said gibs.

2. In a jointer having a stationary table supporting bed and an adjustable table supporting bed on the stationary bed, the stationary bed comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one side of said inclined edge portions, a table top welded to the upper edge portions of said upright plates, a pair of subassemblies between said upright plates in the region of said inclined edge portions and welded thereto, one subassembly 25 being adjacent the upper end of said inclined edge portions and the other adjacent the lower end thereof, each subassembly including a pair of upright transversely arranged plates with the advanced plate elevated above the other plate, extensions projecting upwardly at the side edge portions of said last plates, and a gib welded to the corresponding extensions of said plates, the gibs being inclined corresponding to that of said inclined edge portions and being arranged adjacent thereto, and means on said adjustable bed 30 slidably engaging said gibs.

3. In a jointer having a stationary table supporting bed and an adjustable table supporting bed on the stationary bed, the stationary bed comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one side of said inclined edge portions, a table top welded to the upper edge portions of said upright plates, a pair of subassemblies between said upright plates in the region of said inclined edge portions and welded thereto, one subassembly being adjacent the upper end of said inclined edge portions and the other adjacent the lower end thereof, each subassembly including a pair of upright transversely arranged plates with the advanced plate elevated above the other plate, extensions projecting upwardly at the side edge portions of said last plates, and a gib welded to the corresponding extensions of said plates, the gibs being inclined corresponding to that of said inclined edge portions and being arranged adjacent thereto, the adjustable table bed comprising a pair of upright laterally spaced longitudinal sheet metal plates, upwardly inclined lower edge portions on the inner end portions 35 of said last plates, the inclination thereof corre-

sponding to that of said first longitudinal plates, a plurality of spaced transverse spacer plates between and welded to the inner sides of said last longitudinal plates, a pair of spaced sub-assemblies between said last longitudinal plates in the region of said inclined edge portion, each subassembly including vertically inclined guide strips at opposite sides and slidably engaging the gib on said first subassemblies respectively.

4. In a jointer having a stationary table supporting bed and an adjustable table supporting bed on the stationary bed, the stationary bed comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one side of said inclined edge portions, a table top welded to the upper edge portions of said upright plates, a pair of subassemblies between said upright plates in the region of said inclined edge portions and welded thereto, one subassembly being adjacent the upper end of said inclined edge portions and the other adjacent the lower end thereof, each subassembly including a pair of upright transversely arranged plates with the advanced plate elevated above the other plate, extensions projecting upwardly at the side edge portions of said last plates, and a gib welded to the corresponding extensions of said plates, the gibs being inclined corresponding to that of said inclined edge portions and being arranged adjacent thereto, the adjustable table bed comprising a pair of upright laterally spaced longitudinal sheet metal plates, upwardly inclined lower edge portions on the inner end portions of said last plates, the inclination thereof corresponding to that of said first longitudinal plates, a plurality of spaced transverse spacer plates between and welded to the inner sides of said last longitudinal plates, a pair of spaced subassemblies between said last longitudinal plates in the region of said inclined edge portion, each subassembly including vertically inclined guide strips at opposite sides and slidably engaging the gibs on said first subassemblies respectively, and plate means carrying said gibs welded to said last plates respectively, said guide strips being spaced outwardly from said inclined edge portion.

5. In a jointer having a stationary table supporting bed and an adjustable table supporting bed on the stationary bed, the stationary bed comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one side of said inclined edge portions, a table top welded to the upper edge portions of said upright plates, a pair of subassemblies between said upright plates in the region of said inclined edge portions and welded thereto, one subassembly being adjacent the upper end of said inclined edge portions and the other adjacent the lower end thereof, each subassembly including a pair of upright transversely arranged plates with the advanced plate elevated above the other plate, extensions projecting upwardly at the side edge portions of said last plates, and a gib welded to the corresponding extensions of said plates, the gibs being inclined corresponding to that of said inclined edge portions and being arranged ad-

jacent thereto, the adjustable table bed comprising a pair of upright laterally spaced longitudinal sheet metal plates, upwardly inclined lower edge portions on the inner end portions of said last plates, the inclination thereof corresponding to that of said first longitudinal plates, a plurality of spaced transverse spacer plates between and welded to the inner sides of said last longitudinal plates, a pair of spaced subassemblies between said last longitudinal plates in the region of said inclined edge portion, each subassembly including vertically inclined guide strips at opposite sides and slidably engaging the gibs on said first subassemblies respectively, plate means carrying said gibs welded to said last plates respectively, said guide strips being spaced outwardly from said inclined edge portion, and means for securing said adjustable bed in adjusted position including members carried by said stationary bed and frictionally engaging said guide strips.

6. In a jointer having a stationary table supporting bed and an adjustable table supporting bed, the stationary bed comprising a pair of laterally spaced upright longitudinal sheet metal plates, horizontally disposed upper edge portions on said plates, downwardly inclined upper edge portions at the inner ends of said plates, brace means connecting intermediate portions of said plates, a table top connected to the upper horizontal edge portions of said plates, means interposed between said plates in the region of said downwardly inclined edge portions providing sets of laterally spaced parallel gibs, the adjustable bed comprising a pair of laterally spaced, upright sheet metal plates having upwardly inclined edge portions at the inner ends thereof, a table top on said last plates, and means interposed between said last plates in the region of said inclined edge portions and including guide strips slidably engaging said gibs respectively.

7. In a jointer having a stationary table supporting bed and an adjustable table supporting bed, the stationary bed comprising a pair of laterally spaced upright longitudinal sheet metal plates, horizontally disposed upper edge portions on said plates, downwardly inclined upper edge portions at the inner ends of said plates, brace means connecting intermediate portions of said plates, a table top connected to the upper horizontal edge portions of said plates, means interposed between said plates in the region of said downwardly inclined edge portions providing sets of laterally spaced parallel gibs, the adjustable bed comprising a pair of laterally spaced, upright sheet metal plates having upwardly inclined edge portions at the inner ends thereof, a table top on said last plates, means interposed between said last plates in the region of said inclined edge portions and including guide strips slidably engaging said gibs respectively, means to effect shifting movement of the adjustable bed relatively to the stationary bed, and means for positively securing the adjustable bed in the position of adjustment.

8. In a jointer having a stationary table supporting bed and an adjustable table supporting bed on the stationary bed, the stationary bed comprising a pair of laterally spaced upright longitudinal sheet metal plates, downwardly inclined upper edge portions at the inner ends of said plates, a plurality of spaced transverse spacer plates between and welded to the inner sides of said upright plates and disposed at one

side of said inclined edge portions, a table top welded to the upper edge portions of said upright plates, a pair of subassemblies between said upright plates in the region of said inclined edge portions and welded thereto, one subassembly being adjacent the upper end of said inclined edge portions and the other adjacent the lower end thereof, each subassembly including a pair of upright transversely arranged plates with the advanced plates elevated above the other plate, extensions projecting upwardly at the side edge portions of said last plates, and a gib welded to the corresponding extensions of said plates, the gibs being inclined corresponding to that of said inclined edge portions and being arranged adjacent thereto, the adjustable table bed comprising a pair of upright laterally spaced longitudinal sheet metal plates, upwardly inclined lower edge portions on the inner end portions of said last plates, the inclination thereof corresponding to that of said first longitudinal plates, a plurality of spaced transverse spacer plates between and welded to the inner sides of said last longitudinal plates, a pair of spaced subassemblies between said last longitudinal plates in the region of said inclined edge portion, each subassembly including plate means extending transversely of said last longitudinal plates and welded thereto, extension means on said plate means projecting outwardly beyond said last inclined edge portion, and guide strip means on said extension means slidingly engaging said gibs respectively.

9. In a jointer having a stationary table supporting bed and an adjustable table supporting bed, the stationary bed comprising a pair of laterally spaced upright longitudinal sheet metal

plates, horizontally disposed upper edge portions on said plates, downwardly inclined upper edge portions at the inner ends of said plates, brace means connecting intermediate portions of said plates, a table top connected to the upper horizontal edge portions of said plates, means interposed between said plates in the region of said downwardly inclined edge portions providing sets of laterally spaced parallel gibs, the adjustable bed comprising a pair of laterally spaced, upright sheet metal plates having upwardly inclined edge portions at the inner ends thereof, a table top on said last plates, a transverse plate closing one end of said upright plates and extending laterally therebeyond, a table extension on said laterally extending portion of said transverse plate, a welded seam between said table extension and said last table top, a welded seam between said transverse plate and said last table top, means interposed between said last upright plates in the region of said inclined edge portions and including guide strips slidingly engaging said gibs respectively, means to effect shifting movement of the adjustable bed relatively to the stationary bed, and means for positively securing the adjustable bed in the position of adjustment.
